BRACE

Harry Cleon Boone, Lubbock, Tex.

Application July 18, 1944, Serial No. 545,477

2 Claims. (Cl. 2—44)

1

This invention relates to braces for holding and supporting the body of a person having back or other injuries, and is particularly directed to forms of braces for use in connection with back injuries.

It has been found that the braces shown in this application support the back adequately while they are at the same time comfortable in use and allow adequate freedom for breathing and other necessary bodily actions.

While a plaster cast completely surrounding the body initially forms a satisfactory brace, so far as support for the body and the back-bone is concerned, yet it is uncomfortable and inconvenient because of the failure to provide for the necessity for breathing, eating, etc. Moreover, by reason of the movement of the cast caused by breathing, eating, etc., it becomes loose after a time and does not form a proper support.

One of the objects therefore of the present invention is the provision of a satisfactory body brace of sufficiently strong and rigid construction to support an injured back adequately and for a sufficient length of time, which brace is, nevertheless, so formed that it is comfortable in use.

A further object of the invention is the provision of a metal body brace covered with a softer material and having openings formed at appropriate places.

A further object of the invention is the provision of a metal frame covered with a softer material, which softer material is formed with extensions for securing the unit about the body of the wearer.

One feature of the invention is the provision of a steel frame formed with upper and lower openings through which the body extends, and with front and rear openings for the purpose of comfort, which steel frame is provided with a leather covering securely holding the metal frame in position and eliminating discomfort in the use of such brace.

A further feature of the invention is the provision of a steel frame having appropriate openings, having a leather cover and having leather straps secured to said cover and arranged to secure the brace to the body of the user.

Further objects and features of the invention may be seen from a study of the accompanying specification and drawings, in which:

Figure 1 is a view in front elevation of one of my improved braces, shown in place on a portion of the body of the wearer (such portion of the body being shown in outline) and having por-

tions broken away and sectioned to disclose more adequately the construction of the brace;

Figure 2 is a plan view having portions broken away and portions shown in section;

5 Figure 3 is a view in elevation having a portion broken away and a portion shown in section.

Figure 4 is a view in front elevation showing a modified form of my invention;

Figure 5 is a view in plan of the structure of 10 Figure 4; and,

Figure 6 is a view in side elevation of the modification shown in Figure 4.

Referring specifically to the drawings, it may be seen that I have shown in Figure 1 a brace 11 fitted on a body 12 and formed substantially as a portion of a cylinder, but having openings above and below through which the body 12 may extend, and also having opening 13 in the rear end and opening 14 in front, for comfort of the

15 wearer. While the cylinder is, except for said opening 13, complete in the rear and on both sides, in the front there is a break across which tabs 15, 16, 17 and 18, extend toward each other, but do not contact normally with each other, 20 when the brace is worn. That is, the brace is an incomplete cylinder with a space in the front thereof. The tabs 15 and 16 are arranged to be secured together by a strap 19 and the tabs 17 and 18 are similarly arranged to be secured together by a strap 21.

Referring more specifically to the construction of the brace it may be seen that the brace is formed of a metal (preferably steel) plate 22 having a slight spring, cut and bent in appropriate form and covered with a leather cover 23, which is formed of leather sheets 24 and 25, secured to each other and extending on both sides of and completely covering steel plate 22. The leather is secured so as to completely cover the 35 plate by stitchings 26, which stitchings extend completely around the periphery thereof and around the periphery of the openings therein. The straps 19 and 21 are secured by stitchings 27 and the buckles 28 and 29 are similarly 40 stitched to the tabs 15 and 17.

I have found that a cloth covering is not satisfactory because it will give and also is objectionable for sanitary reasons. I therefore use leather as a cover for the steel plate.

45 In the modification shown in Figures 4 to 6 inclusive, the brace 111 is similarly provided with upper and lower openings through which the body may protrude, and with a rear opening 113 and a forward opening 114 and similarly has a 50 metal sheet 122 and leather covering 123 com-

prising sheets 124 and 125. It is provided with straps 119 and 120 and buckles 128 and 129, and is stitched similarly to the preferred embodiment as shown at 126.

It is also provided with upwardly extending projections 131, 132, 133 and 134, which extend above the level of the arm-pits and provide braces for upper portions of the body where such support is necessary. This embodiment of my invention is constructed especially for cases where there are breaks in the back-bone in the upper part of the back of the wearer.

In putting on and adjusting for the wearer a brace constructed according to my invention, the straps 19 and 20 (or 119 and 120) are released from the buckles 28 and 29 (or 128 and 129) and the brace is put around the body in a manner similar to the usual manner of putting on a belt, the natural spring of the steel plate allowing the front tabs to be separated farther while the brace is positioned. Thereafter the straps are reinserted in the buckles and tightened and the brace then forms a perfect support for the body. At the same time the wearer, because of the openings in front and rear of the brace, may breathe normally and naturally and similarly, because of said openings, the distention of the stomach after eating does not affect the fit of the brace.

It is to be understood that the above described embodiments of my invention are for the purpose of illustration only, and various changes

may be made therein without departing from the spirit and scope of the invention, as defined by the following claims.

I claim:

- 5 1. For use in supporting the body of a person having injuries to his back, a brace comprising a metal sheet bent substantially in the form of a disconnected cylinder, provided with projections at the disconnected portion extending toward each other and with straps connecting such projections, formed with openings front and rear whereby the wearer may breathe and eat normally without destroying the bracing effect of the brace, and also provided with two upstanding tabs in the front one on each side and with two upstanding tabs in the rear one on each side for supporting the shoulders above the level of the arm-pits.
- 10 2. A torso engaging brace comprising a generally cylindrical metal sheet interrupted in front and provided with vertically spaced upper and lower integral projections extending toward one another at the interruption, and flexible means connecting the projections to form a unitary structure, the back engaging portion of said sheet having an opening therein and said projections and flexible means defining an opening in the front of the structure whereby the wearer may breathe and eat normally while wearing the brace.
